UNITED STATES PATENT OFFICE.

CHARLES HOWARD HOOK, OF PITTSBURGH, PENNSYLVANIA.

BOILER.

Application filed January 31, 1924. Serial No. 689,652.

To all whom it may concern:

Be it known that I, CHARLES HOWARD Hook, a citizen of the United States, and a resident of Pittsburgh, in the county of Allegheny and State of Pennsylvania, have invented a new and useful Improvement in Boilers, of which the following is a specification.

This invention relates to water heaters made up of a plurality of cast cooperating sections.

The objects of the invention are to so make the cooperating sections that a maximum exposure of surface to hot gases may be obtained; and that the hot gases may be guided in a tortuous path through the heater so as to partially obstruct their flow, causing them to come in contact with a maximum amount of surface of water tubes. More specifically an object of the invention is to so position transverse hollow water carrying tubes in the sections that when two cooperating sections are properly positioned against each other, adjacent water tubes of the same level in the two sections will be alternately close together, and spaced apart, in consecutive pairs. Other objects and advantages will be apparent to those familiar with the art from the following specification.

Referring to the drawings, Fig. 1 is a side elevation and partial section showing a single section of a heater embodying this invention, this section being in place upon a normal carrying base; Fig. 2 shows a partial vertical section through the heater shown in Fig. 1, upon the line II-II thereof.

Low pressure heaters for use in the heating of dwellings and buildings are ordinarily made of a plurality of cooperating cast iron sections, adapted when fitted together to form a water-containing boiler or heater all of the interior spaces being connected together so as to permit a circulation of water therethrough, the sections being designed to secure a large exposure of surface to gases of combustion used for heating. Such apparatus is either used for generating steam or else for heating water to be circulated through a system of radiators. The individual sections are cast from iron or iron alloy, in well known manner, and the particular method of making is no part of this invention.

These sections are made with hollow top

and side portions, and with transverse connecting tubes between the side wall chambers. My invention relates to the particular form and positioning of these transverse water tubes.

Referring to the drawings a heater illustrating my invention is shown comprising a hollow base member 1 having openings 3 and 2 therein for the insertion of fuel pipes, and for observation doors. Burners of any suitable form are positioned in the chamber 4 formed inside the hollow base 1, which supports the heater sections 5, 6, 7, 8, 9, 10 thereon. It is understood that the particular heating means employed is not a part of the invention, and any suitable form of furnace may be used. The heater sections comprise hollow side wall forming casings 11 and 12, which have lateral openings 13 and 14 therethrough, at the tops of the compartments 11 and the bottoms of compartments 12, as illustrated. These openings form a passage through which water may circulate from one section to the next adjacent one when the sections are normally positioned by being clamped together side by side to form a heater as illustrated in Fig. 2.

Transverse hollow tubes extend across between the compartments 11 and 12, and these tubes are spaced apart a material distance from each other in vertical direction, the lowermost tubes being symmetrically arranged in the middle portions of the heater section, the tubes above being positioned out of symmetrical middle position, alternately on each side of the middle plane, approximately in outer alignment with one or the other of the side planes of the heater section. For example referring to section 5 of Fig. 2 the lowermost tube 15 is symmetrically positioned with respect to the middle plane of the section, the next upper tube 16 is positioned unsymmetrically with respect to the middle plane, the tube being moved over to the left just short of the outer plane of the section, the next tube 17 being positioned unsymmetrically with respect to the middle plane, to the right almost to the inner plane of the section, the next tube 18 corresponding in position to the lower tube 16, and the last tube 19 corresponding in position to the tube 17, etc.

The next heater section 6 has its tubes, which are marked with numbers corresponding to the tube of section 5 with the addition

of the letter "a"—arranged in similar order, except that the tubes of the same level after the lowermost, are positioned unsymmetrically in opposite order to the arrangement 5 of the tubes of section 5. That is to say tube 16^a of section 6 is out of symmetry by being positioned near the inner plane of the section whereas tube 16 of section 5 is unsymmetrically positioned in the opposite direction. 10 This arrangement is as if the section 6 were identical with the section 5, but turned around.

Additional sections 7 and 9 correspond 15 in arrangement of tubes to that of section 5, and additional sections 8 and 10 correspond in arrangement of tubes to that of section 6, and so on for whatever number of heater sections may be employed.

It will be noted that tubes 17 and 17^a, 20 19 and 19^a, etc., in the assembled heater have a slight clearance, in the form of a narrow slot or crack running across the heater. On the other hand the sections 18 and 18^a, 16 and 16^a, etc., are positioned apart a substantial 25 distance, so that there is afforded a free passage therebetween for hot gases. This arrangement results in the tubes in vertical pairs being first relatively close together and the next pair relatively far apart. 30 The water tubes are made in a special oblong shape, so as to expose a maximum amount of lower surface to the rising hot gases.

The gases of combustion from the chamber 1 pass upward and strike against the lowermost water tubes 15, 15^a, 15^b, etc. These being symmetrically arranged in the middle portions of the heater sections provide 35 passages on each side thereof through which the gases travel upwardly. Above the lowermost series of the water tubes, the gases can not pass freely between the sections 16^a—16^b, 16^c—16^d, etc., but are caused to pass to and through the passages between the sections 16 and 16^a, 16^b and 16^c, etc. Having 40 passed through these passages the gases necessarily divide and flow laterally to reach the passages between the sections 17^a, 17^b, 17^c, 17^d, etc., and so on, passing upward through the heater and around the tubes in a tortuous path. Thus the hot gases come into contact with a maximum surface of the tubes, and also their upward travel is so restricted that they are retained in the 45 heater long enough to give up a maximum amount of their heat by absorption through the walls of the heater sections and transverse tubes.

The narrow space between the tubes, as 50 for example between tubes 17 and 17^a, 16^a and 16^b, etc., is not intended to permit any material flow of hot gases therethrough, but is just sufficient to prevent the formation of a dead pocket of gas between those two tubes.

At the top the gases of combustion pass upward through central openings 20^a provided between the top compartment 20 of each section by offset abutting portions 21 as illustrated in Fig. 1, and out through a 70 flue connected with a central opening 23 in a cap plate 24, as illustrated.

In order that the gases may not be drawn to the middle portion of the tubes by the draft of the centrally placed openings 20^a, 75 baffles are provided beneath those openings, formed by offset portions 25 extending from the walls of compartment 20, as illustrated in Fig. 1. These contact in adjoining sections as illustrated in Fig. 2, and cause the 80 gases to pass into the openings 20^a from each side of the baffles formed by projections 25. This tends to keep the hot gases spread out in the heater and to prevent pockets.

It will be observed that when the boiler 85 or heater is assembled the tubes of the several sections are arranged in successive horizontal rows. Consequently, in spite of the staggered arrangement to secure maximum contact with gases of combustion, the tubes 90 may be cleaned by a brush inserted from the side or front.

The result of this arrangement is a water heater of increased efficiency, which may be made without any extra expense as compared to similar heaters now in use. A maximum contact of hot gas with heating 95 surface is obtained, flow of gases through the heater is unobstructed by dampers or other elements that do not contain water, 100 and yet the flow is retarded sufficiently by the actual water-containing elements to secure the desired retention of gases until their effective heat has been sufficiently absorbed.

I claim:

1. A water heater composed of a plurality of adjacent connected sections, each section having side and top compartments and transverse hollow tubes, some of the tubes of each section being arranged in staggered relation with respect to the middle plane of the section, and the sections being assembled so that the staggered tubes of the same level in adjacent sections are alternately positioned relatively close together and far apart in vertical order.

2. In a water heater comprising a plurality of clamped together hollow sections adapted to contain water and comprising 120 top and side compartments and similar transverse horizontally connecting tubes of greater width than height in cross section and of lesser width than the side compartments, the tubes of each section being alternately offset on opposite sides of the middle plane of the section, and tubes at the same level of each two adjacent sections being arranged to be alternately spaced near together and materially apart in ascending 125 130

order above the lowermost tubes in each section that adjacent tubes of the same level are alternately spaced relatively close together and far apart in ascending order, the tubes being positioned in the assembled heater in successive horizontal rows, whereby free spaces through the heater for cleaning are provided above and below each row of tubes.

3. A water heater comprising a plurality of cast sections arranged to fit together to form a unitary container, each section having side compartments and transverse connecting tubes, the tubes being alternately offset on opposite sides of the middle plane of each section, and the sections so arranged

10
